UNITED STATES PATENT OFFICE.

PERCIVAL NICHOLSON, OF ARDMORE, PENNSYLVANIA.

SPHYGMOMANOMETER.

1,093,199.

Specification of Letters Patent. Patented Apr. 14, 1914.

Application filed June 21, 1913. Serial No. 775,068.

To all whom it may concern:

Be it known that I, PERCIVAL NICHOLSON, a citizen of the United States, residing at Ardmore, in the county of Montgomery and State of Pennsylvania, have invented certain improvements in Sphygmomanometers, of which the following is a specification.

My invention is a sphygmomanometer having improved means whereby there is provided an accurate instrument having separable sections adapted for ready dissociation, compact inclosure within a small case, and ready association for use.

The improvements are characterized by efficient means for preventing the escape of the indicating fluid, connecting the jointed parts and adjusting such parts to the desired relation.

The nature of the improvements is disclosed in the following description and the accompanying drawings in illustration thereof.

In the drawings, Figure 1 is a perspective view of a closed case for containing the sphygmomanometer with the parts in their incased relation; Fig. 2 is a front elevation of the same with the lid of the case erected and the parts of the sphygmomanometer thereon; Fig. 3 is a front elevation of the instrument with the parts in their operative relation; Fig. 4 is a broken sectional side elevation of the mechanism; Fig. 5 is a broken sectional front view; and Fig. 6 is a broken elevation of parts of the sectional tube and its connections.

The apparatus, as illustrated in the drawings, comprises the case 1 having the lid 2 connected thereto by hinges 3. The lid is held in the closed position by the catch 4, having the slide 5 movable transversely in the ways 6, and the angular slot 7 in the end of the case in which the catch is engaged. The lid is held in the erected position by the catch 8 fixed thereon and having a lateral projection 8' adapted, when the lid is elevated, to spring into the notch 9' of a resilient catch 9 fixed within the case. The catches 8 and 9 are disengaged; so that the lid can be lowered, by pressing the button 9'' projecting from the catch 9 through the case and thereby moving this catch laterally.

A metal tube 10, a glass cistern 11 having the neck 11' connected with the tube, and a glass tube 12 having its bottom connected

with the bottom of the cistern by the U-bend 13, are fixed to the lid which, when closed, incloses them. The tube 10 has a flange 10' on its lower end and the neck 11' has a threaded sleeve 14 cemented thereon, the flange and sleeve being connected by a coupling collar 15 engaging the flange in revoluble relation and screwing on the sleeve. 60

An angular bearing 16, provided with a slot 16', is engaged to the lid by a screw 17 which passes through the slot, whereby the bearing is adjustable laterally. Clips 16^a containing slots 16^b are fixed in adjustable relation to the bearing 16 by the screw 16^c, 65 the clips having the resilient jaws 16^d. A fixture comprising the valve casing 20 and the socket or collar 20' containing the fenestration 20^a is held by the clips 16^a, the jaws 16^b engaging the socket 20' so that the fixture can be adjusted. The outer end of the tube 12, which contains the tapered socket 12', is fixed in the socket 20', extending beyond the fenestration so as to be wholly surrounded at its extremity by the socket. A 70 clip 18 engages the bend 13, which is movable therethrough, and contains the slot 18' through which the screw 19 passes into the lid, permitting a transverse adjustment of the bend. 75

A conical valve 21 is journaled in the casing 20 and has therein the diametral passage 21' adapted for registration with the openings 20^a and 20^b of the casing, the valve having the slot or fenestration 21'' 80 parallel with the aperture 21' and adapted to register with the fenestrations 20^a and 20^b of the fixture. A handle 22 is fixed to the valve and extends in the direction of the aperture and slot, the handle extending beyond the end of the lid when the valve is open and lying within the limits of the lid when the valve is closed, so that the lid cannot be closed when the valve is open and can be closed when the valve is closed, thereby 85 preventing the escape of the indicating fluid, mercury, by closing the lid with the valve open. 90

A glass tube 23, having the tapered lower end 23', is adapted to pass through the casing 20 and valve 21, when the passage 21' is in registration with the socket 20' and the aperture 20'', into the tapered seat 12' of the tube 12, in the associated relation of the parts. When the instrument is not in use, 100 105 110

the tube 23 is withdrawn from the tube 12, through the casing 20 and valve 21, and inserted in the tubular holder 24 (having the resilient section 24') fixed to the lid 2 by 5 the clip 25, and the valve 21 is turned to close the tube 12.

The scale section 26 is provided with the bearings 26' containing slots 26'', the lid 2 is provided with the bearings 27 which frictionally engage the parts 26', and the screws 27' extend through the parts 27 into the slots 26'', the scale being made adjustable thereby. A scale section 28 is connected to the section 26 by the hinge 29 so that the former section can be folded down upon the latter, the section 28 being provided with a spring clasp 30 which engages the section 26 to hold the sections in the folded relation when not in use.

20 The tube 10 has a socket 10^a communicating with the interior of the tube through a valve 31, the socket being adapted to receive a tapered nipple 32 connected, through the tube 33, with the air bulb 34. A second socket 10^b of the tube 10 is adapted for receiving a tapered nipple 35 connected, through the tube 36, with a pneumatic cuff 37. A third socket 10^c has therein a needle valve 38 by means of which air is allowed 30 to escape from the tube under control.

It will be understood that when not in use the apparatus is protected by the case, by which it is completely inclosed, the nipples 32 and 35 being withdrawn from the respective sockets 10^a and 10^b, the tube 23 disposed in its holder 24, the scale section 28 folded down, and the valves 21, 31 and 38 closed. When it is desired to use the apparatus, the catch 4 is disengaged from the slot 7, the lid 2 is elevated so that the catches 8 and 9 engage, the nipples 32 and 35 are inserted in their respective sockets, the valves 21 and 31 opened, the scale section 28 turned upon its hinge into line with the section 26, the latter is adjusted to the level of the mercury, and the lower end of the tube 23 is passed through the casing 20 and valve 21 into its engagement with the part 12' of the tube 12.

50 Have described my invention, I claim:

1. In a sphygmomanometer, means comprising a cistern and a tube connected therewith for containing a fluid, means connected therewith for applying pressure thereto and 55 for obliterating the pulse, a second tube, means comprising a valve through which said second tube is connected with said first tube and by which said first tube is adapted to be closed, and a scale for reading the height 60 of the liquid in said tube or tubes.

2. In a sphygmomanometer, means comprising a tube for containing a fluid, means connected therewith for applying pressure thereto, a second tube, and means comprising a socket engaging an end of said first

tube, a valve casing, and a valve through which an end of said second tube extends into registration with said first tube.

3. In a sphygmomanometer, means comprising a tube for containing a fluid, means connected therewith for applying pressure thereto, a second tube, and means comprising a fenestrated socket in which an end of said first tube is disposed, a valve casing through which an end of said second tube is adapted to extend into registration with said first tube, and a fenestrated valve in said casing through which said second tube extends, said second tube passing freely through said valve.

4. In a sphygmomanometer, means comprising a tube containing a fluid, means connected therewith for applying pressure thereto, a second tube, and means comprising a fenestrated socket in which an end of said first tube is engaged, a valve casing through which an end of said second tube extends into the end of said first tube in said socket, and a fenestrated valve through which said end of said second tube passes freely and by which said first tube is adapted to be closed when said second tube is withdrawn.

5. In a sphygmomanometer, the combination with a case having a lid, means comprising a valve casing and communicating with the interior thereof a fenestrated socket fixed to said lid, means comprising a glass tube having an end fixed in said socket, a fenestrated valve with a diametral passage therethrough revoluble in said casing to control flow through said tube, a device movable with said valve and engaging said case to prevent the closure of said lid when said valve is open, and a tube adapted to extend through said casing and the passage in said valve when in the open position into registration and in alinement with said tube first named, said second tube when inserted preventing the operation of said valve.

6. In a sphygmomanometer, the combination with a case having a lid, of means comprising a glass cistern and tube having connected ends; means for communicating pressure to said cistern comprising a metal tube fixed to said lid and a coupling having a 115 revoluble sleeve connecting said metal tube with said cistern; a fixture having a movable connection with said lid, a fenestrated socket in which an end of said glass tube is fixed and a valve casing; a fenestrated valve in said casing and having a passage therethrough, and a glass tube extending freely through said valve into said glass tube first named.

7. In a sphygmomanometer, the combination with a case having a hinged lid, a fixture comprising a fenestrated socket and a valve casing fixed to said lid, means comprising a glass tube having an end in said socket, a fenestrated valve containing a 125

diametral passage and adapted to turn in said casing, a glass tube adapted for passing freely through said casing and valve into registration with said tube first named, 5 and a scale having hinged sections for reading a column of liquid in said tubes, a section of said scale being connected in adjustable relation to said lid.

8. In a sphygmomanometer, the combination with a case having a hinged lid, a fixture comprising a socket and a valve casing fixed to said lid, a glass tube having an end fixed in said socket, a valve revolvable in said casing and having a handle which prevents 15 the closing of said lid by engaging the case

when said valve is open, a catch fixed to said lid, a resilient catch connected with said case and adapted for automatically engaging said first catch to hold said lid open, and a push button whereby said second 20 catch is operated to disengage it from said first catch.

In testimony whereof I have hereunto set my hand this 20th day of June, 1913, in the presence of the subscribing witnesses.

PERCIVAL NICHOLSON.
